FLAMING LIGHTER

Donald A. Richards, Yonkers, N. Y., assignor to
Vestalite Corporation, New York, N. Y., a corporation of New York

Application February 21, 1934, Serial No. 712,340

4 Claims. (Cl. 67—7)

This invention relates to flaming lighters employing a catalyst, and my improvement is directed to a lighter of this class wherein the catalyst is supported by a base member that is in removable engagement with a tubular housing which is lined interiorly with an absorbent element, to be charged with vaporizable fuel.

The removable base is provided with air admission means, and a cylindrical cover, adapted to fit slidably over the tubular housing, and carrying interiorly a concentric sleeve adapted to separate the catalyst from the absorbent element when the cover is telescoped over the housing in its closed position, said air admission means, in the operation of withdrawing the cover, serving through the suction created in such withdrawal to provide a rush of air into the tubular housing, for co-action with vapor from the fuel, to react upon the catalyst, whose consequent incandescence will ignite the vapor, thus producing the flame.

It will be understood that upon removal of the base with the supported catalyst, and the removal also of the cover with its catalyst separating sleeve, then the absorbent lining of the tubular housing may be suitably charged with liquid fuel.

Other features and advantages of my invention will hereinafter appear.

In the drawing:—

Figure 1 is a side sectional elevation of the lighter.

Fig. 2 is a section on the line 2—2 of Fig. 1.

Fig. 3 is an elevation, partly broken away, showing the lighter elements, with the exception of the base and catalyst.

Fig. 4 is a detail of the lighter base and catalyst.

In said views let 1 indicate the lighter base, which may be of suitable cross-sectional contour, and is here shown, for example, as circular.

Said base has the surrounding wall 2 with an inturned flange 3, from which a neck-like, exteriorly threaded projection 4 extends upwardly. A tubular member 5 extends centrally through the base and projects upwardly therefrom, for purposes to be described hereinafter. Said member 5 may be drawn integrally from the base material. The base supports a pad or gasket 6 that surrounds member 5 and whose upper surface is bounded by the flange 3.

At 7, I have indicated a blob or pellet of spongy platinum composition, constituting the catalyst, which is connected with strands 8 of platinum

wire that are strung upon a supporting frame 9. Said frame 9 is suitably carried by the base, and is here shown as provided with a coil 10 that fits snugly over the member 5, for such support.

A tubular housing member 11, open at both ends, is provided with an interior thread at one end whereby it may be screwed upon and released from the neck-like projection 4 of the base. Also, at the same end member 11 may have an annular abutment 12, which may be knurled, to facilitate the connecting and disconnecting operations.

The member 11 is lined interiorly with absorbent material 13 for saturation with vaporizable fuel, such as alcohol, and is in surrounding relation with the catalyst, for co-action therewith when the lighter is in operation.

Also a cover 14 is provided in the form of a cylinder, with a closed end 15, said cover being adapted to fit slidably over housing 11. Said cover 14 carries an inner tube 16 which is in concentric spaced relation therewith, and is adapted, at its lower end, to impinge against the gasket 6, to effect therewith a vapor tight enclosure for the catalyst when the cover has been telescoped over housing member 11 to the lighted closed position. In the example shown the upper, closed end 17 of inner tube 16 is fixed to the top 15 of cover 14, to integrate these members 14, 17.

It being understood that the catalyst for its reaction requires to absorb the vapor from the fuel, in the presence of an adequate supply of air, therefore it will be noted that in the act of removing the cover 14, with its attached inner tube 16, thereby the catalyst becomes exposed to vapor from the absorbent element 13 and also a quota of fresh air is drawn into the housing by the suction created through the admission tube 5.

When the absorbent element is to be recharged with fuel the base, carrying the catalyst, is removed and then the cover 14 can be withdrawn from housing 11, thus leaving the absorbent material free for recharging.

Variations within the spirit and scope of my invention are equally comprehended by the foregoing disclosure.

I claim:—

1. A flaming lighter comprising an apertured base, a supporting frame mounted on said base, a catalyst supported on said frame, an open ended housing mounted on and extending from said base, absorbent material to be charged with vaporizable fuel carried on the interior of said housing in proximity to said catalyst, a removable cover slidable over said housing, and an

inner sleeve carried by said cover positioned between said absorbent material and said catalyst and co-acting with said base to separate said absorbent material and said catalyst, said cover being adapted in its removal to draw atmospheric air through said apertured base and to remove said sleeve to allow communication between said absorbent material and said catalyst.

5 2. A flaming lighter comprising a base, a hollow tube on said base to provide an air passage, a supporting frame mounted on said tube, a catalyst supported on said frame, an open ended housing on and extending from said base, absorbent material to be charged with vaporizable fuel carried on the interior of said housing in proximity to said catalyst, a removable cover 10 slidable over said housing, and an inner sleeve carried by said cover positioned between said absorbent material and said catalyst to co-act 15 with said base to separate said absorbent material and said catalyst, said cover being adapted in its removal to draw atmospheric air through the passage and to remove said sleeve to allow communication between said absorbent material and said catalyst.

20 3. A flaming lighter comprising a base, a gasket on the inner surface of said base, a hollow tube on said base to provide an air passage through said base and said gasket, a supporting frame mounted on said tube, a catalyst supported on said frame, an open ended housing 25 removably mounted on and extending from said base

to surround said catalyst, an absorbent interior lining for said housing to be charged with vaporizable fuel, a removable cover slidable over said housing, and an inner sleeve carried by said cover positioned between said absorbent lining and said catalyst to co-act with said gasket to separate said lining and said catalyst, said cover being adapted in its removal to draw atmospheric air through said passage and to remove said sleeve to allow communication between said lining and said catalyst.

4. A flaming lighter comprising a base, a threaded flange on said base, a gasket on the inner surface of said base surrounded by said flange, a hollow tube secured to said base and extending through said base and said gasket to provide an air passage, a supporting frame mounted on said tube, a catalyst supported on said frame, a housing sleeve threaded on said flange to surround said catalyst, an absorbent interior lining for said housing sleeve to be charged with vaporizable fuel, a removable cover slidable over said housing sleeve, and an inner sleeve carried by said cover positioned between said absorbent lining and said catalyst with its lower edge impinging against said gasket to separate said lining and said catalyst, said cover being adapted in its removal to draw atmospheric air through said passage and to remove said inner sleeve to allow communication between said lining and said catalyst.

DONALD A. RICHARDS.
